CANDY CONFECTION

Alfred Bianchi, Brooklyn, N. Y., assignor to The
Bianchi Co., New York, N. Y., a firm

Application April 9, 1949, Serial No. 1,881

Term of patent 14 years

(Cl. D82—2)

To all whom it may concern:

Be it known that I, Alfred Bianchi, a citizen of the United States, residing at Brooklyn, in the county of Kings and State of New York, have invented a new, original, and ornamental Design for a Candy Confection, of which the following is a specification, reference being had to the accompanying drawing, forming part thereof.

Fig. 1 is a front elevational view of a candy confection showing my new design.

Figs. 2 and 3 are top and bottom views, respectively, of a candy confection shown in Fig. 1, and

Figs. 4 and 5 are right and left side elevational views, respectively, of the candy confection shown in Fig. 1.

I claim:

The ornamental design for a candy confection, as shown.

ALFRED BIANCHI,
